UNITED STATES PATENT OFFICE

117,143

DESIGN FOR A SAWING MACHINE

Charles Handelman, Chicago, Ill.

Application November 3, 1938, Serial No. 80,845

Term of patent 7 years

To all whom it may concern:

Be it known that I, Charles Handelman, a citizen of the United States, residing at Chicago, in the county of Cook and State of Illinois, have invented a new, original, and ornamental Design for Sawing Machine, of which the following is a specification, reference being had to the accompanying drawings, forming part thereof.

Fig. 1 is a perspective view showing the front, top and one end of a sawing machine showing my new design;

Fig. 2 is a perspective view showing the front, top, the same end and a portion of the rear thereof, and

Fig. 3 is a perspective view on a slightly enlarged scale showing the rear, top and other end of the sawing machine.

I claim:

The ornamental design for a sawing machine, as shown.

CHARLES HANDELMAN.
